MACHINE FOR LABELING WEBS

Johannes Menschner, Rosswein, Germany

Application November 10, 1937, Serial No. 173,776
In Germany October 16, 1936

10 Claims. (Cl. 216—25)

This invention relates to the art of periodically attaching perforated or printed gummed paper labels along a running web to identify its length or to make it more easy to sever portions of desired lengths from the whole. According to one of the known procedures for doing this a paper strip is printed with the desired markings at regular intervals, gummed on its back and rolled. There upon this roll is placed within a rotating drum running at the same circumferential speed as the web wherein a tool effects the moistening of the paper, then a separating of the portion which is to be affixed on the cloth at any one point, and then the affixing of the label.

15 A disadvantage of this procedure is that not only the part to be cut off but also an area surrounding or adjacent to such part is moistened, because the moistening occurs before the cutting. This results in the paper strip becoming sticky, 20 in the affixed mark showing an irregular outline and also in the knife or punch soon becoming so soiled and sticky that it no longer functions. Furthermore, where a single element serves to both separate and place the labels, it is very 25 difficult to adjust it with the degree of accuracy required by these two steps.

An object of the present invention is to provide a machine avoiding the above disadvantages by employing different elements to cut, to gum, 30 and to affix the labels, and to have these tools operate in the order just named.

This machine is adapted to use both labels which are cut off at sections of a strip and labels which are stamped out from a broader strip. 35 Moreover, the machine can be adapted to print the labels immediately before they are affixed if it is desired to do this instead of using labels which are already printed.

An embodiment of my invention will be hereinafter described with reference to the accompanying drawings in which:

Fig. 1 represents a vertical section through the axis of the marking drum.

Fig. 2 represents a section of the marking drum taken along the line II—II of Fig. 1 looking in the direction of the arrows.

Fig. 3 represents a section of the marking drum taken along the line III—III of Fig. 1 looking in the direction of the arrows.

50 Figs. 4A to 4E inclusive represent partial sections on an enlarged scale through the marking drum taken along the line III—III of Fig. 1. Taken in connection with Fig. 3, they therefore show the mouth portion of the marking drum in six different positions as it rotates about its axis.

Fig. 5 represents a partial vertical section through the axis of a modified form of marking drum.

The marking drum consists of a cylindrical protective casing 1 attached at one end to the 5 spoked support wheel 2 which has at its center a hub 3 rotatably mounted on an axle 5 fixed horizontally in support 4. At the end of hub 3 which is away from support 4 it enlarges into a supporting disc 16 which extends to, and helps 10 in positioning, the cylindrical protective casing 1. A second supporting disc 6 is held by the cylindrical protective casing 1 at a distance from supporting disc 16. 1 denotes a roller over which the web *n* moves in the direction of the arrows 15 shown in Figs. 1, 3, and 4E. The relation of the web to the marking drum is that shown in Fig. 1, and the marking drum is caused to rotate at a surface speed approximately equal to that of the web through the engagement of gear wheel 20 8, which is mounted on spoked support wheel 2, with suitable gearing not shown.

Connected to the end of stationary axle 5 which protrudes into the casing is a gear wheel 9 which meshes with the gear wheels 10, 11, and 25 12, supported respectively by being fixed to shafts 13, 14, and 15, which are rotatably supported by supporting discs 6 and 16. Since it is through the operation of these gears that the machine works, I have shown them of equal size 30 with gear wheel 9, so that during one complete rotation of the marking drum, each of these three gears will exactly complete one functional cycle. If it is desired to have longer distances 35 between the labels on the web, the ratio of gear wheel 9 to gears 10, 11, and 12, can be so selected that a label will be affixed at only every two or more revolutions of the marking drum.

In Fig. 1, 17 represents a roll of paper, printed on its inside surface at regular intervals, and 40 gummed on its outside surface. The paper leads from this roll through the mouth portion of the machine, between drawing-off rollers 19 and 20 and through to the space between supporting disc 16 and spoked support wheel 2, where it is stored 45 and from which it can from time to time be removed through the openings 25 between the spokes of wheel 2.

Within the marking drum and supported by guide 47 which is connected to second supporting disc 6 lies what I have termed the mouth portion of my machine, which cooperates with an opening in the protective casing 1. This mouth portion may be further described as consisting of a die 22 having as a part of its outer 50 55

mouth a rim 38 which partially closes said outer mouth, a slideable cutting punch 21, and a slideable plunger 23 which is guided in the punch 21. Between the die 22 and the punch 21 there is provided a slot through which the paper strip 18, after it is drawn off of roll 17, is guided. From the paper strip thus guided through the mouth portion the labels *m* are cut out as follows:

10 In Fig. 4A the punch 21, the die 22, and the plunger 23 are in retracted positions. Punch 21 and plunger 23 have slid into guide 47 and have cleared the way for the advancement of the paper strip 18 which passes between guide 47 and die 15 22.

10 In Fig. 4B the same portion of the machine is shown in a more advanced position. The punch, die, and plunger remain in the same position but the paper strip 18 has, in a manner still to 20 be described, been advanced a predetermined distance corresponding to the distance between its printed portions, so that the printed portion is exactly opposite the punch 21.

Fig. 4C shows the same portion of the machine 25 after it has rotated still further and it will be seen that the new label *m* has been punched out of the paper strip 18 by the advance of punch 21 and plunger 23 relative to die 22.

Fig. 4D represents the same part of the machine 30 in a still further rotated position showing that punch 21 has remained in the same position relative to the casing 1 while die 22 has moved radially outward with respect to the casing 1 so that it protrudes a small distance beyond said casing. Moreover, plunger 23 has 35 advanced with respect to punch 21 and, with its head 39, it has advanced the label *m* until the perimeter of the label is resiliently pressed against the rim 38 which is a part of the outer mouth of die 22 and which partially closes the same, thus effectually closing and protecting the bore of the die and presenting the gummed side of label *m* to the moistening roller 57 which, together with the rest of the moistening device 40 58, is located as shown in Fig. 4D. Thus the gummed surface of the label will be moistened by the roller.

Fig. 4E shows the same portion of my machine 45 after it has rotated still further and is ready to contact the web *n*. Up to this time the label has been securely held in the bore of the die 22. In this position it is being pressed against the web, and die 22 begins a retractive movement while plunger 23 remains stationary, thus positively freeing the label from the bore of the die and securely affixing it to the web.

In Figs. 1 and 3 the same portion of my machine is shown after it has rotated a slight distance beyond the position shown in Fig. 4E, a 50 position which I have identified as position F which is where the die is retracted while the plunger is advanced, completing the labeling operation.

Between position F as shown in Figs. 1 and 3 55 and the position shown in Fig. 4A the plunger, after leaving the label securely on the web, and the punch 21 are retracted to the position previously described.

The movements required for the above described motions of the punch, the die, and the plunger are derived from shafts 13, 14, and 15 respectively which are rotated by gears 10, 11, and 12 through the action of cams 40, 41, and 42 which are secured respectively to said shafts. 60 Cam 40 actuates through a roller the lever

44 pivoted on pivot 43 and being attached at its other end by means of a driving pin 45 to a slot controlling the motion of punch 21 as it slides within the guide 47. Spring 46 serves to keep lever 44 constantly in contact with cam 40.

Die 22, which is slideable along guides 47, 48, and 49 is similarly governed by the action of cam 41 by means of the stud 52 which is pressed against said cam by means of springs 50 and 51. Said stud is unitary with die 22 and the cam is so arranged, as shown in Fig. 3, that the retraction of said die will be sudden.

Cam 42 serves to control the action of plunger 23 through the lever 55 which is pivoted on pivot 54 and carries a roller bearing against said cam and held against said cam by spring 53. A driving pin 56 operatively connects the outer end of said lever with a slot on the inner end of plunger 23.

The axis of drawing-off roller 20 is carried by 20 lever 26 and is strongly pressed against drawing-off roller 19 by means of a strong spring 27. The motion of drawing-off roller 19 is controlled by an attached ratchet wheel 28 which is actuated by pawl 31 which in turn is pivoted on an arm 25 attached to plunger 34 held by guides 32 and 33 and bearing a roller 36 which imparts a reciprocation to said plunger through the cooperation of said roller with cam 37 driven by shaft 15. It will be noted that said cam and said 30 roller are held together by spring 35. By this means the drawing-off rollers are intermittently advanced by a distance which is carefully predetermined with respect to the amount of motion necessary to bring the next printed material directly in place in the die, each time the machine rotates. In connection with the pawl and ratchet mechanism just described for advancing the strip, I provide at the other end of roller 19 a ratchet wheel 29 cooperating with a 40 stationary pawl 30 to prevent any rotation of roller 19 in an unwanted direction.

It will thus be seen that in operation, as the web passes over roller 7 the marking drum rotates at approximately the same speed as the 45 web and as it turns the slideable cutting punch moves towards the periphery, cutting out a label which is thereupon pushed in a peripheral direction until it is only held by the contact between the plunger and the rim 38 of the outer 50 mouth of die 22, whereupon it passes a moistening device and proceeds to contact the web, whereupon the die 22 is withdrawn, leaving only a plunger to press the label against the cloth. Thereupon the punch and plunger are withdrawn, the strip material from which the labels are cut is moved ahead by a distance equal to 55 one label, and the machine is ready to repeat this cycle of motions.

Various changes may be made in the structure 60 of this device without departing from my invention. For instance, it is possible to construct the drawing-off rollers 19 and 20, which serve in Fig. 1 as pulling rollers for the paper strip, as pushing rollers. In Fig. 5 I have shown this 65 modification. It will readily be seen that the operation of the machine is the same except that the paper strip is gripped between the roll of paper and the punch instead of being gripped after it leaves the punch. This construction 70 might be preferable where severed portions of the strip itself are applied as labels.

It will be understood that various changes may be resorted to in the form, construction, arrangement, and material of the several parts without 75

departing from the spirit and scope of my invention, and hence I do not wish to be limited to the particular embodiment herein shown and described except as they may be included in the claims.

What I claim is:

1. In a web labeling machine of the character described, means adapted to sever a label from a supply of severable labels, means adapted to moisten the label so severed, and means adapted to press the label so severed and moistened against the running web.

2. In a web labeling machine of the character described, means adapted to sever a label from a supply of severable labels, means adapted to moisten the label so severed, means adapted to move the label so severed and moistened at a speed substantially equal to the speed of the running web and in substantially the same direction, and means adapted to press the label so severed and moistened against the running web.

3. In a web labeling machine of the character described, a rotatable drum, a punch and die therein adapted to sever a label from a supply of severable labels, means adapted to moisten the label so severed, and means adapted to press the label so severed and moistened against the running web.

4. In a web labeling machine of the character described, a rotatable drum, a punch and die therein adapted to sever a label from a supply of severable labels, moistening means proximate to said drum, a plunger adapted to present the severed label to said moistening means and to press the label so severed and moistened against the running web.

5. In a web labeling machine of the character described, a rotatable drum, a punch and die therein adapted to sever a label from a supply of severable labels and to reciprocate in a radial direction with respect to said drum, moistening

means proximate to said drum, a plunger adapted to present the severed label to said moistening means and to press the label so severed and moistened against the running web, and a rim adapted to cooperate with said plunger to retain the moistened and unaffixed label. 5

6. In a web labeling machine of the character described, a rotatable drum, a punch and die therein adapted to sever a label from a supply of severable labels and to reciprocate in a radial direction with respect to said drum, moistening means proximate to said drum, a plunger smaller in area than a label adapted to present the severed label to said moistening means at a greater distance from the axis of said drum than the point at which the label is severed from its supply, and adapted to press the label so severed and moistened against the running web, and a rim adapted to cooperate with said plunger to retain the moistened and unaffixed label. 10 15 20

7. A machine as characterized in claim 1 including a step-by-step label supply advancing mechanism and intermittent operating means therefor. 25

8. A machine as characterized in claim 1 including a step-by-step label supply advancing mechanism and intermittent operating means therefor, said advancing mechanism being located on the side of said severing means opposite the supply of labels. 30

9. A machine as characterized in claim 1 including a step-by-step label supply advancing mechanism and intermittent operating means therefor, said advancing mechanism being located between the supply of labels and said severing means. 35

10. A machine as characterized in claim 5 wherein the rim has an aperture therethrough, said aperture being smaller in cross section than a severed label. 40

JOHANNES MENSCHNER.
